CLAIM

The ornamental design for an exercise apparatus, as shown and described.

DESCRIPTION

FIG. 1 is a perspective view of our new design of an exercise apparatus;

FIG. 2 is a front view of the design of FIG. 1;

FIG. 3 is a back view of the design of FIG. 1;

FIG. 4 is a first side view of the design of FIG. 1;

FIG. 5 is a second side view of the design of FIG. 1;

FIG. 6 is a bottom view of the design of FIG. 1; and,

FIG. 7 is a top view of the design of FIG. 1.

The broken lines shown in the Figures are for the purposes of illustrating portions of the exercise apparatus, which form no part of the claimed design.

The band is shown with a symbolic break in its length.
The appearance of any portion of the article between the
break lines forms no part of the claimed design.
